[57] CLAIM

The ornamental design for a combined airplane and pumping station, as shown and described.

DESCRIPTION

FIG. 1 is a perspective view of a combined toy airplane and pumping station showing our new design;

FIG. 2 is a left side elevational view thereof;

FIG. 3 is a front elevational view thereof;

FIG. 4 is a top view of the pressure gauge shown separately for clarity of illustration;

FIG. 5 is a bottom view of FIG. 1; and,

FIG. 6 is a right elevational view of FIG. 1.
